(57) **CLAIM**

The ornamental design for a straddle seat for a vehicle as shown and described.

DESCRIPTION

FIG. 1 is a perspective view taken from a front, left, top side of a straddle seat for a vehicle according to a first embodiment of our design;

FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a perspective view taken from a front, left, top side of a straddle seat for a vehicle according to a second embodiment of our design;

FIG. 9 is a rear view thereof;

FIG. 10 is a front view thereof;

FIG. 11 is a right side view thereof;

FIG. 12 is a left side view thereof;

FIG. 13 is a top view thereof;

FIG. 14 is a bottom view thereof;

FIG. 15 is a perspective view taken from a front, left, top side of a straddle seat for a vehicle according to a third embodiment of our design;

FIG. 16 is a rear view thereof;

FIG. 17 is a front view thereof;

FIG. 18 is a right side view thereof;

FIG. 19 is a left side view thereof;

FIG. 20 is a top view thereof; and,

FIG. 21 is a bottom view thereof.

Throughout the Figures, where shown, the dashed lines are included for the purpose of illustrating portions of the article which form no part of the claimed design.

1 Claim, 21 Drawing Sheets
